UNITED STATES PATENT OFFICE.

EMORY B. VOORHEES, OF OVID, MICHIGAN.

CASKET-LOWERING APPARATUS.

SPECIFICATION forming part of Letters Patent No. 655,137, dated July 31, 1900.

Application filed June 9, 1900. Serial No. 19,763. (No model.)

To all whom it may concern:

Be it known that I, EMORY B. VOORHEES, a citizen of the United States, residing at Ovid, in the county of Clinton and State of Michigan, have invented new and useful improvements in Casket-Lowering Apparatus, of which the following is a specification.

My invention relates to a safety lowering apparatus for use at graves or vaults to lower caskets or coffins therein; and the invention consists of the combination and arrangement of parts, substantially as hereinafter described and claimed.

The primary object of my invention is to provide for folding the casket-lowering apparatus into a compact form.

A further object of my invention is to provide for folding the casket-lowering apparatus in such a way as not to interfere with its efficiency when in use in lowering a casket or coffin into the vault.

These objects I accomplish by the mechanism and combination of parts illustrated in the accompanying drawings, in which—

Figure 1 shows a plan view of my casket-lowering apparatus when unfolded and in position for use. Fig. 2 shows also a plan view of the frame folded in one direction, dotted lines showing the position of the end fold; and Fig. 3 shows a perspective view of the side pieces.

Similar letters refer to similar parts throughout the several views.

A B and A' B' show the longer sides of the frame.

C and C' show the ends of the frame, which fold with the sections B B'.

F and F' show the end of the frame.

H and H' show the hinges which allow the longer sides of the frame to be folded together, so that one will lie in close proximity to the other.

E E represent the hinges which connect the sections A and B and the sections A' and B'.

W W represent the webs upon which the coffin or casket rests before it is lowered into the grave.

The mechanism for lowering the casket or coffin is entirely inclosed and concealed by

the framework shown in the drawings, and 50 inasmuch as the same forms no part of my invention is not illustrated in the drawings.

My device is folded in the following manner: Referring now to Fig. 1, the side pieces A' B' and the end section C' F' are turned 55 upon the hinges H H' so that C' rests upon C, B' upon B, A' upon A, and F' upon F, which will leave the frame in the position shown in Fig. 2. After the frame has been folded, as above described, and not before, the section 60 B B', being connected by the hinged hinges E E, is folded down into the position shown by the dotted lines in Fig. 2. By these two operations the frame is but one-half its original width and is shortened by substantially 65 the length of the section B B' and can readily be placed in the box or shell which is used to inclose the coffin or casket.

It will be noted that inasmuch as the hinges E and E' cannot be brought into use until the 70 side pieces have been folded together, as above described, the entire apparatus or frame will remain rigid when opened or unfolded and that by the method of folding I have described the efficiency of the device is 75 in no way decreased.

Having thus described my invention, what I claim to have invented, and desire to secure by Letters Patent, is—

A device of the character described, comprising a sectional frame or structure, with the sections of its end pieces, each, joined by a hinge having its axis arranged horizontally and the sections of its side pieces each joined by a hinge having its axis arranged vertically 85 at right angles to the axis of the hinge connecting the end sections, said hinges for the side pieces being coincident when the sides are folded the one upon the other, substantially as set forth.

In testimony whereof I have hereunto set my hand in presence of two subscribing witnesses.

EMORY B. VOORHEES.

Witnesses:

JOHN HIGH,
W. J. MARTIN.
